UNITED STATES PATENT OFFICE.

CHARLES J. GRIFFITH, OF ST. LOUIS, MISSOURI.

RAILWAY-CROSSING.

1,162,858.

Specification of Letters Patent.

Patented Dec. 7, 1915.

Application filed January 20, 1913. Serial No. 743,138.

To all whom it may concern:

Be it known that I, CHARLES J. GRIFFITH, a citizen of the United States, residing at the city of St. Louis, State of Missouri, have invented a new and useful Railway-Crossing, of which the following is a specification.

My invention relates to improvements in railway crossings wherein the four crossing rails are formed integral, thereby providing 10 a construction devoid of bolts, rivets and like fastening devices, and providing a very strong, rigid structure which is well able to withstand the vibration and pounding incident to the passage of car wheels over 15 the intersecting rails.

Further objects of my invention are, to construct a railway crossing having rails which are substantially hollow and of approximately inverted V-shape in cross section, and further to arrange hardened metal 20 inserts at the points where the flange grooves in the tops of the rails intersect each other.

To the above purposes my invention consists in certain novel features of construction and arrangement of parts hereinafter more fully described, claimed and shown in the accompanying drawings, in which—

Figure 1 is a top plan view of a pair of intersecting rails constructed in accordance 30 with my invention, a portion of one of said rails being shown in horizontal section. Fig. 2 is a cross section taken approximately on the line 2—2 of Fig. 1. Fig. 3 is a cross section of a modified form of the intersecting rails. Fig. 4 is a cross section of a further 35 modification. Fig. 5 is a cross section of a further modified form of the rail. Fig. 6 is a detail section showing the bottom of the flange groove inclined upwardly toward the point where the flange grooves intersect. Fig. 7 is a plan view showing one of the hardened metal inserts in the tops of the rails at the point where the same intersect. Fig. 8 is a cross section taken approximately on 45 the line 8—8 of Fig. 7.

As shown in the drawings, each rail of my improved crossing has a body portion which is substantially of inverted V-shape in cross section, said body portion comprising 50 a pair of inclined webs or walls 10, and formed integral with the lower ends thereof are base flanges 11.

Formed integral with the upper ends of the webs or walls 10 is a ball 12 and a flange 55 guard 13, and between said ball and flange

guard is formed a flange groove 14. Four of the rails so formed are cast integral with each other to form a crossing, and formed integral with the ends of said rails are extensions 15 which are adapted to overlap 60 and receive the ends of ordinary track rails 16.

Immediately adjacent to the points where the rails intersect the walls or webs 10 are formed upright or vertical, as designated 65 by 17, thereby providing openings 18 immediately adjacent to the points of intersection, and which openings are adapted to receive core blocks which support the cores located between the inclined walls or webs 70 10 when the crossing is cast.

In the modified form shown in Fig. 3 the base flanges 11 extend outwardly from the lower ends of the webs or walls 10, and in the modification shown in Fig. 4 the walls or 75 webs 10 are tied together by a horizontally disposed web 19.

In the modification shown in Fig. 5 the upper ends of the inclined webs or walls 10 unite with a short, vertically disposed web 80 20, with the upper end of which is formed integral the ball and flange guard.

In the modification illustrated in Fig. 6 the bottom of the flange groove 14 is gradually inclined upward toward the point 85 where said grooves intersect, and which construction prevents the wheel from dropping into the intersecting groove during the passage of the wheel over the crossing for the reason that the flange of the wheel rides 90 upon the elevated bottom of the flange groove.

In Figs. 7 and 8 I have illustrated the crossing rails as being provided with hardened metal inserts 21 positioned in the tops 95 of the rails at the points where the same intersect, said inserts being provided with flange grooves which coincide with the flange grooves 14. This construction is designed to decrease the wear which ordinarily 100 occurs at the points where the flange grooves intersect.

The hardened metal inserts are only used when the crossing is cast, and said inserts are positioned in the mold before the metal 105 of which the crossing is formed is poured.

A railway crossing of my improved construction is comparatively simple, can be readily cast in a single piece, is very strong 110 and substantial and can be produced much

cheaper than a crossing made up of a number of pieces which are united by means of bolts or rivets.

It will be readily understood that minor changes in the size, form and construction of the various parts of my improved railway crossing can be made and substituted for those herein shown without departing from the spirit of my invention, the scope 10 of which is set forth in the appended claims.

I claim:

1. The herein-described railway crossing comprising intersecting crossing rails formed integral with each other, each rail comprising a pair of webs, portions of which are parallel and other portions being inclined and united at their upper ends, a ball and a flange, and hardened metal inserts rigidly fixed in the tops of the balls and flanges of said rails at the points where the same intersect and which inserts are held in position by the metal of which the rails are formed.
2. The herein-described railway crossing comprising intersecting crossing rails formed integral with each other, each rail comprising a pair of webs, portions of which are parallel and other portions being in-

clined and united at their upper ends, a ball and a flange, and hardened metal inserts 30 rigidly fixed in the tops of the balls and flanges of said rails at the points where the same intersect, which inserts are provided with flange grooves and are held in the rails by the metal of which said rails are formed. 35

3. The herein-described railway crossing comprising intersecting crossing rails formed integral with each other, each of which rails comprises a pair of webs, portions of which are parallel and other portions being inclined and united at their upper ends, base flanges integral therewith, a ball and flange guard integral with the upper ends of the inclined webs and hardened metal inserts seated in the tops of said rails at the points where the same intersect, which inserts are rigidly held in position by the metal of which the rails are formed.

In testimony whereof I hereunto affix my signature in the presence of two witnesses.

this 17th day of January, 1913.

CHARLES J. GRIFFITH.
